US00D800648S

(12) **United States Design Patent** (10) **Patent No.:** **US D800,648 S**
(45) **Date of Patent:** **** Oct. 24, 2017**

(54) **SOLAR PANEL**

(71) Applicant: **Xiamen Topunive Technology Co., Ltd.**, Xiamen (CN)

(72) Inventors: **Huaqiang Mei**, Xiamen (CN); **Xiaoyuan Xiao**, Xiamen (CN); **Mingjin Chen**, Xiamen (CN)

(73) Assignee: **XIAMEN TOPUNIVE TECHNOLOGY CO., LTD.**, Xiamen, Fujian (CN)

(**) Term: **15 Years**

(21) Appl. No.: **29/583,906**

(22) Filed: **Nov. 9, 2016**

(51) LOC (10) Cl. **13-02**

(52) U.S. Cl.

USPC **D13/102**

(57) **CLAIM**

The ornamental design for a solar panel, as shown and described.

DESCRIPTION

FIG. 1 is a perspective view of solar panel showing my present design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line portion of the figure drawings is included to show portions of the article that forms no part of the claimed design.

1 Claim, 5 Drawing Sheets
